UNITED STATES PATENT OFFICE.

JOHN V. WHITBECK, OF CLEVELAND, OHIO.

DESIGN FOR A REAR CURTAIN FOR AN AUTOMOBILE.

51,192.

Specification for Design.

Patented Aug. 21, 1917.

Application filed November 28, 1916. Serial No. 133,989. Term of patent 14 years.

To all whom it may concern:

Be it known that I, JOHN V. WHITBECK, a citizen of the United States, and a resident of Cleveland, county of Cuyahoga, and State of Ohio, have invented a new, original, and ornamental Design for Rear Curtains for Automobiles, of which the following is a specification, reference being had to the accompanying drawing, forming a part thereof.

The figure represents a rear elevation of a rear curtain on an automobile.

I claim:

The ornamental design for a rear curtain for an automobile as shown.

JOHN V. WHITBECK.

In the presence of—

A. F. MARTIN,
CLAYTON F. DU FIEF.
